225,093

CASUAL SHOE OR THE LIKE

Adolf Dassler, Am Bahnhof, 8522 Merzogenaurach, near Nuremberg, Germany

Filed Mar. 12, 1971, Ser. No. 123,921

Claims priority, application Germany Oct. 24, 1970

Term of patent 14 years

Int. Cl. D2—04

U.S. Cl. D2—310

Fig. 1

Fig. 2

Fig. 3

Fig. 4

Fig. 5

Fig. 6

FIG. 1 is a side elevational view of a causal shoe showing my new design;

FIG. 2 is a front elevational view thereof;

FIG. 3 is a top plan view;

FIG. 4 is a rear elevational view;

FIG. 5 is a side elevational view of the side opposite that shown in FIG. 1; and

FIG. 6 is an enlarged fragmentary sectional view taken on the line 6—6.

I claim:

The ornamental design for a casual shoe or the like, as shown and described.
